UNITED STATES PATENT OFFICE.

SIDNEY S. SAMUELS, OF BAYSIDE, NEW YORK.

DESIGN FOR A CHILD'S ONE-PIECE FUR GARMENT.

59,288.

Specification for Design.

Patented Oct. 4, 1921.

Application filed May 13, 1921. Serial No. 469,383. Term of patent 7 years.

To all whom it may concern:

Be it known that I, SIDNEY S. SAMUELS, a citizen of the United States of America, residing at Fourth street, Bayside, Long Island, New York, have invented a new, original, and ornamental Design for a Child's One-Piece Fur Garment, of which the following is a specification, reference being had to the accompanying drawings, forming part thereof.

In the drawings, Figure 1 illustrates a front view and Fig. 2 a rear view of a child's one-piece fur garment, showing my new design, Fig. 3 showing a cross-section thereof on line 3—3 of Fig. 2.

I claim:

The ornamental design for a child's one-piece fur garment, as shown.

SIDNEY S. SAMUELS.
